ENGAGING IMPELLERS PUMP

Filed Aug. 9, 1944

UNITED STATES PATENT OFFICE

2,487,721

ENGAGING IMPELLERS PUMP

Robert J. Minshall, Shaker Heights, Ohio, assignor, by mesne assignments, to Borg-Warner Corporation, Chicago, Ill., a corporation of Illinois

Application August 9, 1944, Serial No. 548,681

6 Claims. (Cl. 103—126)

1

The present invention relates to fluid displacement apparatus, and more particularly to pumps of the rotary type.

It is one of the principal objects of this invention to simplify the construction of a pump of the rotary type such as contemplated herein and to improve the efficiency, operation and dependability of such pump.

Another principal object of this invention resides in providing means to prevent entrapment of fluid between the compressor members and thereby eliminate an objection inherent in the meshed tooth type of gear pump.

Another object of this invention is to provide a pump wherein oppositely rotating blades are brought together in tip engagement during the final stage of the cycle of operation.

A further object is to provide a dual-chambered pump having two rotors that are provided with radially movable members such as blades for compressing the fluid and wherein a blade on one rotor is retracted by tip engagement with a yieldingly opposed member on the other rotor.

A still further object is to provide a pump wherein each compression member or blade is ported and there is a valve-control passage in the rotor adjacent each compression member that is adapted to be opened to communicate with the compression chamber for venting pressure fluid when a predetermined pressure has been attained.

It is another object of this invention to provide a pump wherein a minimum of clearance is provided between the rotors, and to effect a positive seal between the high pressure and low pressure sides of the pump.

Additional objects, aims and advantages of the invention contemplated herein will be apparent to persons skilled in the art after the construction and operation of the pump assembly is understood from the within description.

It is preferred to accomplish the numerous objects of this invention and to practice the same in the substantially the manner hereinafter fully described and as more particularly pointed out in the appended claims. Reference is now made to the accompanying drawings that form a part hereof, wherein:

Fig. 1 is a fragmentary transverse section with portions in elevation, the view being taken along the plane of line 1—1 on Fig. 2 and looking in the direction of the arrows;

Fig. 2 is a longitudinal vertical section along the plane of line 2—2 on Fig. 1 looking in the direction of the arrows; and

2

Fig. 3 is a fragmentary end view of a pair of compressor members or blades that have been yieldably retracted by tip engagement with each other.

The drawings are to be understood as being more or less of a schematic character for the purpose of disclosing a typical or preferred form of the improvements contemplated herein. In these drawings like reference characters identify the same parts in the different views.

The pump shown in the drawings comprises a housing assembly consisting of substantially cylindrical walls 5 and 6 forming communicating compression chambers A and B respectively that receive the fluid to be compressed through the inlet stub 4. The margins at one side of these cylindrical walls 5 and 6 are connected by a transverse wall 7 that is preferably formed integral therewith and the other margins of said walls 5 and 6 have lateral flanges to which a closure plate 8 is secured in any suitable manner preferably by bolts or the like. The rotors 9 and 10 are revolvably mounted in the chambers A and B and have their respective trunnions 11 and 12 suitably journaled in the housing. A flanged bushing 13 is seated in a bored boss in the wall 7 to receive one end of the trunnion 11, and a similar flanged bushing 14 is mounted in a bored boss on the wall 7 to receive the corresponding end of the other trunnion 12. The other end of the trunnion 11 is journaled in a bore of a bushing plate 15 preferably of circular outline and similarly the corresponding end of the other trunnion 12 is journaled in a circular bushing plate 16.

As seen in Fig. 2 the inner faces of the bushings 13 and 14, and the corresponding inner faces of the bushings 15 and 16 bear against the end faces of the rotors 9 and 10. The bushings 15 and 16 are spring loaded by providing them with sockets 17 and 18 respectively to receive coil compression springs 17a and 18a. The outer ends of these springs press against the closure plate 8 of the housing in the manner shown to exert their pressure in a direction transverse to bushing plates 15 and 16. Thus the bushings 15 and 16 press against the rotors, which in turn are urged against the opposite bushings 13 and 14 to effect a tight fit. The bushings 15 and 16 have a snug fit in the semi-cylindrical walls 5 and 6 of the compression chambers, and at the point where the peripheries of these bushing plates come into contact with each other they are provided with a transverse bore 19 into which a pin 20 is driven to effect a seal therebetween which prevents

leakage from the discharge side of the pump back to the intake side thereof.

The trunnion 11 projects through its bearing 13 and has a gear 21 anchored to it, and there is also a spline stub 22 projecting beyond said gear for connection with any suitable prime mover such as an electric motor or the like. The corresponding end of trunnion 12 extends through the bushing 14 and has a gear 23 anchored to it that is in mesh with gear 21. These gears 21 and 23 each have the same number of teeth so that said gears operate in synchronized relation to each other and at the same speed but in opposite directions.

As shown in the upper portion of Fig. 1, and also in the upper portion of Fig. 2, the trunnions 11 and 12 are hollow throughout the major portions of their lengths providing longitudinal bores X and Y that extend inward from their ends nearest the closure plate 8. The open ends of these bores are sealed by discs 24 that are forced against shouldered end portions of the bores and after the discs have been seated, the surrounding metal of the trunnions is upset as at 25 (Fig. 2) to tightly retain the discs in position and seal the ends of the trunnions.

The rotors 9 and 10 are provided with a plurality of radially disposed channels or guide slots 26 each of which has its inner portion enlarged as at 27 to provide an inner chamber. These channels 26 and their enlarged portions 27 extend through the ends of the rotors, and the outer portions of the channels 26 are open through the peripheries or circumferences of the respective rotors. These channels 26 receive and guide the compression members which are in the form of elongated blades or teeth 28 having chamfered or beveled outer portions 29 that are oblique to and extend away from the leading faces of the blades. The inner portions of these blades have longitudinally disposed lateral flanges 30 along their opposite edges that are adapted, when centrifugally moved outwardly by the rotation of the rotor, to engage the shoulders formed by proximate portions of the channels 26 and the enlarged inner portions 27 thereof. This arrangement insures the blades being retained in the rotor channels 26 and also permits them to move radially inward during their engagement with the cylindrical surfaces of the chambers A and B that are eccentric to the rotational axes of the rotors.

As seen in the drawings, particularly in section in Fig. 1, the blades each have a plurality of bores 31 that are radially disposed with respect to the axis of the rotor and are spaced with respect to each other transversely of the length of the blades. This affords communication between the compression chambers A and B and the inner chambers 27 that are formed by the enlarged inner portions of the guide channels 26 of the rotor.

As shown in Fig. 1 the rotors are provided with a plurality of pockets 32 extending lengthwise of the rotor as seen in Fig. 2. These pockets 32 constitute a plurality of passageways that register and communicate with circular or annular passageways 33 formed in the bushings 15 and 16 surrounding the trunnions 11 and 12 of the rotor. These passageways 33 have lateral portions 34 extending towards each other and unite in an outwardly extending common passageway between the rotors that discharges into the outlet stub 36 of the housing.

The pockets 32 communicate through apertures

37 with the enlarged portions 27 of the blade guides or channels 26. These apertures are normally closed by elongated valve plates 38 that are yieldably maintained in contact with the walls 5 of the pockets 32 by the movable arms 39 of hairpin shaped springs 40. The other arms 41 of these springs are anchored to the walls of the pockets opposite the valve plates 38.

As seen in Fig. 1, during the rotation of the rotors, the blades 28 will sweep the eccentric surfaces of the compression chambers A and B thereby building up the pressure in front of their leading or chamfered edges 29 of said blades. During the cycle of operation the blades will 10 gradually move inwardly in their guide channels 26 and the compressed fluid will pass into the bores 31 in the respective blades and then into the enlarged portions 27 of the guides back of the inner ends of the blades. When predetermined pressure has been attained, which is predetermined by the tension of the springs 40, the valve plates 38 will open and the pressure fluid will be 15 vented through the apertures 37 into the pockets 32. The pressure fluid will leave the pockets 20 32 by moving into the annular passageways 33, and then pass through the lateral passageways 25 34 which discharge the fluid into the union passageway 35 and leaves the pump through the outlet stub 36.

30 Lubrication of the moving parts is effected by means of an elongated open-ended passageway 42 extending longitudinally in the housing wall 1 in a plane intersecting the axes of the rotor trunnions and communicating with angular 35 grooves 43 and 44 in the respective bushings 13 and 14 that journal the adjacent ends of the trunnions. Diametrically opposite radial bores 45 in the trunnions are registered with the grooves 40 43 and 44 to lead the lubricant into the bores X and Y of the rotors. The opposite ends of the trunnions have radial bores 46 that register 45 and communicate with annular grooves 47 in the bushings 15 and 16. Thus, the lubricant entering the trunnion bores will lubricate the end bearings of the rotors that are remote to the lubricant feed passageway 42.

50 While the present improvements have been described in detail in their present preferred form or embodiment, it will be apparent to persons skilled in the art, after understanding the improvements that various changes and modifications may be made therein without departing from the spirit or scope thereof. It is aimed in the appended claims to cover all such changes 55 and modifications.

I claim:

1. A pump comprising a cylindrical wall and end members defining a compression chamber having inlet and outlet ports; a rotor journaled 60 for rotation in said chamber; radial guide channels in said rotor; compressor blades guided for reciprocal radial movement in said channels to operate in said chamber, said blades having means for conveying pressure fluid radially inward past said blades; longitudinal passageways in said rotor having communication with the pressure fluid conveying means in said blades, said passageways opening through an end of said rotor; valve means controlling communication 65 between said passageways and said fluid conveying means; bushings between said chamber ends and the adjacent ends of said rotor, spring means yieldably urging one of said bushings toward said rotor; and a passageway in one of said 70 bushings communicating with the longitudinal

passageways in said rotor for discharging the pressure fluid through said outlet port.

2. A pump comprising a cylindrical wall and end members defining a compression chamber having inlet and outlet ports; a rotor journaled for rotation in said chamber; radial guide channels in said rotor having enlarged inner regions; blades reciprocable radially in said guide channels, said blades having enlarged inner edges operable in the enlarged inner regions of said guide channels to limit radial outward movement of said blades; passageways through said blades effective to convey pressure fluid to the enlarged inner regions of said guide channels; means in an end member defining an annular passageway around a rotor journal; a branch passageway leading from said annular passageway to said outlet port thereby establishing communication between the adjacent end of the rotor and the outlet port; pockets in said rotor radially inward from said guide channels adapted to discharge into said annular passageway; and valve means adapted to control communication between said pockets and the inner regions of said guide channels.

3. A pump comprising a cylindrical wall and end members defining a compression chamber having inlet and outlet ports; rotors journaled for rotation in opposite directions in said chambers; radial guide channels in said rotors, each channel having an enlarged inner region; blades reciprocable radially in said channels, said blades each having an enlarged inner edge operable in the enlarged regions of said channels to limit radial outward movement thereof; passageways through said blades effective to convey pressure fluid to said enlarged inner regions of the guide channels; means defining passageways in an end member adjacent an end of each rotor and extending between said ends of the rotors and said outlet port; pockets in said rotors radially inward from said guide channels and extending through the ends of said rotors said pockets having constant communication with said end member passageways; and valve means effecting a controlled communication between the pockets of each rotor and the inner regions of the respective guide channels.

4. A pump comprising a cylindrical wall and end plates defining therein a compression chamber having inlet and outlet ports; two radially channeled rotors journaled in said end plates for rotation in said chamber and in surface contact with each other and arranged with their ends in close engagement with said end plates; 55 blades guided for radial reciprocal movement in said rotor channels and being adapted to sweep said cylindrical wall, the blades in one rotor being arranged to be brought into opposed tip engagement with the blades of the other rotor for effecting full retraction of said engaged blades, said blades having means therein for conveying pressure fluid to the radially inner regions of said rotor channels; means defining an annular passageway in an end plate in surrounding re- 65

lation to a rotor journal, said annular passageway being arranged to receive pressure fluid from the radially inner regions of said rotor channels; and means in said end plate establishing communication between said passageway and said outlet port.

5. A pump comprising a cylindrical wall and end plates defining a compression chamber means defining inlet and outlet ports communicating with said compression chamber; a pair of radially channeled rotors journaled in said end plates for rotation in said chamber, said rotors being arranged with their ends engaged with said end plates; blades guided for radial reciprocal movement in said rotor channels and being adapted to sweep said cylindrical wall, said blades having means for conveying pressure fluid to the radially inner regions of said rotor channels; annular passageways spaced from each other in the inner face of the outlet end plate, each said passageway surrounding the adjacent journal of a rotor, said annular passageways being arranged to separately receive pressure fluid from the radially inner regions of the respective rotor channels; and conduits leading from said annular passageways adapted to establish communication between the respective passageways and said outlet port.

6. A pump as defined in claim 5 wherein the blades have chamfered outer portions and the blades in one rotor are arranged to be brought into radially aligned yieldably opposed tip engagement with the blades of the other rotor whereby to effect full retraction of the opposing blades without closing the passageways in said engaged blades.
